UNITED STATES PATENT OFFICE.

ARTHUR TREVOR DAWSON AND GEORGE THOMAS BUCKHAM, OF LONDON, ENGLAND,
ASSIGNORS TO VICKERS SONS & MAXIM LIMITED, OF LONDON, ENGLAND.

AUTOMATIC GUN.

942,167.

Specification of Letters Patent.

Patented Dec. 7, 1909.

Application filed October 23, 1907. Serial No. 398,718.

To all whom it may concern:

Be it known that we, ARTHUR TREVOR DAWSON, lieutenant Royal Navy, director and superintendent of Ordnance Works, and 5 GEORGE THOMAS BUCKHAM, engineer, both subjects of the King of Great Britain, residing at 32 Victoria street, Westminster, London, in the county of London, England, have invented certain new and useful Improvements 10 in or Relating to Automatic Guns, of which the following is a specification.

This invention relates to automatic guns, particularly those of the Maxim rifle caliber pattern and of the kind that are provided 15 with a shoulder piece or a handle-block, the chief object of the invention being to provide a gun of this character that shall be simple in construction and light in weight so as to be easily portable.

20 We will describe our improvements with reference to the accompanying drawings, in which:

Figure 1 is a side elevation of our improved automatic gun provided with a 25 shoulder piece. Fig. 2 is a vertical section showing the internal mechanism on a larger scale. Fig. 3 is a sectional elevation of the lock mechanism on a still larger scale. Fig. 4 is a side elevation, and Fig. 5 a rear end 30 elevation of a modified form of our improved automatic gun having a handle block and intended to be fired from an ordinary tripod or similar mounting. Fig. 6 is a vertical section, and Fig. 7 a sectional plan of the same. Fig. 8 is a vertical section of the breech mechanism showing to a large scale the lock at the commencement of its forward movement after having been retracted. Fig. 9 is a similar section showing the lock 35 advanced almost to its complete forward position, and Fig. 10 shows said lock fully advanced. Fig. 11 is a detail sectional elevation of the safety sear arrangement. Fig. 12 is a side elevation. Fig. 13 a plan, and 40 Fig. 14 a front elevation of the lifting lever and cocking arm, Fig. 13 showing these parts separated but in position to be fitted together.

Like letters of reference indicate similar 45 parts in all the figures.

The improved gun is constructed on the principle of the well known Maxim automatic rifle caliber gun which is supplied with ammunition from a cartridge feed 50 belt; that is to say the breech mechanism

comprises a reciprocating lock A adapted to recoil in guides on the side plates B B of an inclosing casing and to impart motion to a crank shaft C through toggle levers (comprising the crank C' and the connecting rod C²) against the resistance of a spring C³ which in reacting supplies the necessary energy for returning the lock to the firing position and resetting the parts ready for an ensuing discharge, as well as for causing 65 the cartridge feed belt to carry a fresh cartridge into the feed block D. The said block A has the usual vertical moving cartridge carrier E which, during the recoil, is acted upon by suitably arranged stationary 70 cams F F engaging with horns e on the carrier. Lifting levers G actuated by side levers G', are provided for elevating the said carrier as the lock completes its forward movement, thus bringing the carrier 75 into engagement with the rim of the ensuing cartridge that has been meanwhile carried into the feed block D by the movement of the belt. The firing is effected by means of a sliding trigger plate H which is actuated 80 by a trigger and a trigger lever H' at the rear of the breech casing and which acts upon the sear a of the lock mechanism for releasing the cocking arm or tumbler a' and permitting the striker a² to advance under 85 the influence of the main spring a³.

When the trigger is operated, the sliding trigger plate H rocks the sear a and releases its lower end from engagement with the tumbler a'; the main spring a³ then 90 drives the firing pin or striker a² against the cartridge in the gun barrel and thereby fires the gun; the forward movement of the striker a² also causes the tumbler a' to be rocked into a position in which its free end 95 bears upon the connecting rod C². The lock casing is formed with upper and lower lateral flanges the upper A⁴ of which work in corresponding guides B⁴ formed on the cover B'. After the firing of the gun the 100 lock recoils in its guides carrying with it the cartridge carrier E, the flanges e' upon the front face of which grip the rim of the spent cartridge in the gun barrel and the fresh cartridge in the cartridge feed block D thus 105 withdrawing these two cartridges. The horns e on the carrier E meanwhile engage with the stationary cam surfaces F which assist gravity in depressing the carrier E into the position shown in Fig. 8. The car- 110

rier E is free to descend owing to the fact that the recoil of the lock has caused the toggle levers C' C² to move, against the resistance of the spring C³; and as the crank 5 C' turns about the axis of the crank shaft C, the connecting rod C² becomes tilted correspondingly, that is to say, assumes the oblique position shown in Fig. 8, and in so doing moves the side levers G', which form 10 part of said connecting rod, away from the lifting levers G as shown in this figure. The tilting of the connecting rod C² also effects the re-cocking of the striker by raising the free end of the tumbler a' and there- 15 by rocking said tumbler sufficiently for the sear a' to engage with the notch on it.

As the lock returns under the influence of the spring C³, the spent cartridge is ejected through the opening b in the breech casing 20 and the fresh cartridge is inserted into the gun barrel, this cartridge having been maintained in its proper horizontal position by the engagement of the spring-controlled pawl e² with the rim of the cartridge. To 25 ward the completion of the return movement of the lock, the shoulder a⁸ on the safety sear a⁴ engages with a corresponding shoulder a⁹ on the firing pin or striker a² under the influence of the spring a¹⁰ (Fig. 3); also the 30 side levers G' engage with the lifting levers G (as shown in Fig. 9) and thereby cause the cartridge carrier E to slide upward against the face of the gun barrel and feed block, and engage at its upper part with 35 the rim of another fresh cartridge which has meanwhile been fed into the feed block D, the spring controlled pawl e² giving way during this movement. As the toggle levers C', C² become finally straightened out (see 40 Fig. 10), the lever C² depresses the free end of the safety sear a⁴ and thereby disengages it from the striker a². The gun is then ready to be fired again.

The chief feature of novelty of our in- 45 vention consists in that we invert the lock mechanism, that is to say, instead of the tumbler a', the sear a, the main spring a² and the lifting levers G being arranged below the axis of the firing pin they are ar- 50 ranged above it, and the trigger plate H for actuating the said sear is situated at the upper part of the breech casing, namely on the hinged cover plate B', instead of at the bottom of the said casing as heretofore. The 55 lifting levers G instead of being pivoted on an independent axle are mounted on the same axle a⁸ as that upon which the cocking arm or tumbler a' is mounted and they are operated by the side levers G' which form 60 part of the connecting rod C² as in the lock mechanism already in use, except that the said side levers project in an upward direction instead of downwardly. It will be seen that by mounting the cocking arm and 65 lifting levers on the same axle, only two

axle pins are required in the whole of the lock mechanism instead of three as hitherto. The safety sear a⁴ is arranged below the axis of the striker and has its forward end forked to engage with a fixed pin a⁵; near its rear- 70 ward end it has a downward projection a⁶ (Figs. 3 and 11) engaging with a slot a⁷ formed in the bottom of the lock frame, thereby preventing said safety sear from becoming longitudinally disengaged from the 75 pin a⁵, but permitting of its free movement about the said pin during the working of the gun.

In detaching the various parts of the lock mechanism the axis pins about which 80 the sear, the cocking arm, and the side levers move, are removed from the lock frame, and the striker is withdrawn longitudinally, whereupon the free end of the safety sear a⁴ rises under the influence of its spring a¹⁰ 85 and can be readily removed by hand without the necessity of removing therefrom any means of attachment, but merely drawing its forked end away from the pin a⁵, as shown in Fig. 11. The cartridge carrier E 90 is retained in the usual position, i. e. with the horns e at its upper end, but the lifting levers G are adapted to act upon said carrier near its upper end instead of at a point near its lower end. By constructing the 95 lock in this manner we are able to make the same of much less depth than heretofore with the result that the depth of the breech casing can be correspondingly reduced and a diminution in the total weight of the gun 100 effected.

In Figs. 1 and 2 the shoulder piece is in the form of a rifle butt A² and may be made hollow for sake of lightness.

In the modification shown by Figs. 4 to 105 7, we have illustrated our improvements applied to an automatic gun which is adapted to be fired from an ordinary tripod stand or mounting in the well known manner. The rear part of the gun has the usual han- 110 dle block P.

What we claim and desire to secure by Letters Patent of the United States is:—

1. In an automatic gun of the Maxim type, a reciprocating lock consisting in the 115 combination with the striker, the vertically moving cartridge carrier and the side levers, of a cocking arm, a firing sear, and a main spring, all situated above the axis of the striker, lifting levers for the carrier mounted on the same axis as that of the cocking arm and engaging with the carrier at its upper end, a safety sear situated below the axis of said striker, a sliding trigger plate 120 engaging with the firing sear, and means for actuating said trigger plate to fire the gun.

2. In an automatic gun of the Maxim type, a reciprocating lock consisting in the combination with the striker, the vertically moving cartridge carrier, and the side levers, of 130

- a cocking arm, a firing sear, and a main spring, all situated above the axis of the striker, lifting levers for the carrier mounted on the same axis as that of the cocking arm and engaging with the carrier at its upper end, a safety sear situated below the axis of said striker, a sliding trigger plate carried by the cover plate of the breech casting and engaging with the upper end of the 5 said firing sear, and means for actuating said trigger plate to fire the gun.
3. In an automatic gun of the Maxim type, a reciprocating lock consisting in the combination with the striker, the vertically moving cartridge carrier, the side levers, the cocking arm, the firing sear, the main spring, and lifting levers for the carrier, of a pivoted safety sear having a notch therein, a pivot pin in the lock frame with which the 10 said notch engages and on which the safety sear pivots, means for preventing said safety sear from unintentional disengagement from the pivot pin, a sliding trigger plate engaging with the firing sear, and means for 15 actuating said trigger plate to fire the gun.
4. In an automatic gun of the Maxim type, a reciprocating lock consisting in the combination with the striker, the vertically moving cartridge carrier, the side levers, the 20 cocking arm, the firing sear, the main spring, and lifting levers for the carrier, of a safety rear 25 having a forked end, a pin in the lock frame with which the forked end engages, a transverse projection on the safety sear, a slot in the lock frame with which the said projection engages, a sliding trigger plate engaging with the firing sear, and means for actuating said trigger plate to fire the gun.

and lifting levers for the carrier, of a pivoted safety sear having a forked end, a pin in the lock frame with which the forked end engages and on which it pivots, means for preventing the said safety sear from moving longitudinally away from the pin, a sliding trigger plate engaging with the firing sear, and means for actuating said trigger plate to fire the gun. 35

5. In an automatic gun of the Maxim type, a reciprocating lock consisting in the combination with the striker, the vertically moving cartridge carrier, the side levers, the cocking arm, the firing sear, the main spring, and lifting levers for the carrier, of a safety rear 40 having a forked end, a pin in the lock frame with which the forked end engages, a transverse projection on the safety sear, a slot in the lock frame with which the said projection engages, a sliding trigger plate engaging with the firing sear, and means for actuating said trigger plate to fire the gun. 45

In testimony whereof we affix our signatures in presence of two witnesses.
